[57] CLAIM

The ornamental design for an aroma-generating record-type disc, as shown and described.

DESCRIPTION

FIG. 1 is a top plan view of an aroma-generating record type disc showing my new design, the bottom being the same as the top shown;

FIG. 2 is a side elevation thereof; and

FIG. 3 is an enlarged cross-sectional view thereof, with portions broken away for convenience of illustration.

Fig. 1.

Fig. 2.

Fig. 3.
